UNITED STATES PATENT OFFICE.

WILLIAM G. METCALF, OF DAYTON, OHIO.

STAPLING-MACHINE.

SPECIFICATION forming part of Letters Patent No. 641,876, dated January 23, 1900.

Application filed April 26, 1899. Serial No. 714,501. (No model.)

To all whom it may concern:

Be it known that I, WILLIAM G. METCALF, a citizen of the United States, residing at Dayton, in the county of Montgomery and State of Ohio, have invented certain new and useful Improvements in Stapling-Machines; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 This invention relates to improvements in pin-ticket machines.

The object of the invention is to provide a machine with a capacity for making the parts of the ticket and uniting said ticket to the fabric or other article all in one operation.

In the drawings herewith annexed, Figure 1 is a side elevation of the mechanism, the cover being removed to show nothing but the mechanism and supporting-frame; Fig. 2, a similar elevation of the opposite side to that shown in Fig. 1; Fig. 3, a top plan view, the ends of the supporting-frame appearing in section and parts of the mechanism removed; Fig. 4, a section on the line $x-x$ of Fig. 1 looking 20 in the direction of the arrow; Fig. 5, a sectional view of the type-wheels and co-operating devices; Fig. 6, a top plan view of the staple mechanism; Fig. 7, an elevation of the same; Fig. 8, a bottom view of the plunger-guide; Fig. 9, a plan view of the lever through which the platen of the stapling mechanism is operated; Fig. 10, a side view of the ribbon-feeding slide; Fig. 11, a side elevation of the machine; Figs. 12 and 13, different views 25 of the staple plunger or driver; Figs. 14, 15, and 16, detail views of the staple-depositor; Fig. 17, an enlarged elevation of a portion of the vertically-reciprocating bar and the staple-plunger; Fig. 18, an enlarged elevation 30 of the upper end of the operating-rod and connections; Fig. 19, a detail sectional view of the staple-former.

Throughout the specification similar reference characters denote corresponding parts.

35 The main or primarily moving parts consist of a horizontal bar A, movable up and down, and a parallel rock-shaft or rod B. The

former has at one end an upright tubular extension A', which incloses a guide-post A'', secured to the frame C. The other end of 55 the bar A has attached to it a staple plunger or driver a, and said bar also carries a series of type-wheels c and form c', which will be more particularly described hereinafter. The ribbon b from roll b' passes over the stationary platen b'' below the type-wheels and form and is fed intermittently by a reciprocable slide d, which is movable along guides d' d', supported on a bracket d'', attached to the frame C. The upper side of said slide has 60 two inwardly-turned flanges d³ d³, which loosely inclose the edges of the ribbon and keep said ribbon in place on the slide. Two 65 grippers d⁴ d⁴ are pivoted on the sides of the slide to engage with the ribbon when moved 70 out from the position to feed. The said grippers are pressed up by coil-springs d⁵. (See Fig. 10.) Holding pawls or grippers d⁶ d⁶, located between the slide d and the platen b'', hold the ribbon against any back movement. The movement is imparted to the paper-feeding slide d through a depending bar D, which has its upper end pivoted and its lower end forked to engage with a pin d', projecting from a side of the said slide. This 75 bar D has a cam-slot D', partaking of the angularity shown. Engaging with this slot D' is a pin D'', projecting from the bar A, and thereby a pendulum movement is imparted to the bar D.

85 E is a second depending bar, which is pivoted at its upper end to supports in frame C and provided with a cam-slot E', into which a pin E'' from bar A projects, and movement is thus imparted to said bar E. This bar E 90 has a staple-depositor e on its lower end which moves in to dislodge each staple from the former e' into the rear passage e'', from whence it is driven by the point a' of the plunger a. (See Figs. 15 and 16.)

95 The parallel rock-shaft B has an arm B' projecting therefrom, which passes loosely through a loop B'' on the bar A, and thereby said shaft B is oscillated according to the movement of bar A. The ink-pads F are 100 supported on angle-arms F', attached to shaft B, and are moved to and from the type-wheels c and form c'. (See Fig. 5.) The wire f is fed from a roll across the top of the former e' by

means of a gripping-pawl f' , which is pivoted on upright part of a slide f'' . The said slide is inclosed in a slotted housing or guide f^3 , which joins the plunger-guide g' . The said 5 housing or guides f^3 and g' are made fast to the frame C and are thus stationary. The wire-feeding slide f'' has two pins f^4 projecting out, between which an arm f^5 projects. The said arm f^5 is fixed to the rock-shaft B 10 and is moved thereby. f^6 is a stationary holding-pawl mounted on the top of the guide-housing f^3 . This pawl holds the wire while feed-pawl f' moves to engage with the wire to feed it. The wire passes through the 15 slots f^7 of the pawl-supports and below the edge of the cutting-knife g and thence across the upper side of the staple-former e' within the plunger-guide g' . (See Figs. 4 and 7.) The knife g is attached to an arm g'' , projecting from and secured to the rock-shaft B. (See Fig. 4.) After the wire is fed across the 20 top of the staple-former e' and cut the part a'' of the plunger descending on each side of the former bends the ends of the wire, and thus 25 forms a staple. When the plunger thus descends, the staple previously formed is driven by the driving end a' of said plunger. The depositor e moves in to dislodge the staple from the former e' just prior to the descent 30 of the plunger.

Referring, again, to the type-wheels c , each of these has figures throughout its periphery which are printed upon the tickets to indicate the usual data placed on such tickets. The 35 said wheels are fixed to telescopic tubes h , fitting one within the other and turning freely one upon the other. The said tubular or sleeve portions are graduated in length. The innermost tube is loosely supported on a shaft 40 h' , which is mounted in bearings h'' . From these bearings there extend pins h^3 , that pass through ears h^4 on the sides of the bar A. Coil-springs h^5 surround the pins h^3 , and the type-wheels c and form c' are enabled to yield 45 when the impact is made with the platen in printing upon the ribbon. Upon the opposite ends of the sleeves h there are placed toothed wheels i , which have upon their rims figures corresponding to the figures on the wheels c , 50 but occupying different positions. By these means the type-wheels may be turned to change the figures thereon when it is desired to change the printing. The wheels i afford an index or guide for turning the wheels h to 55 the proper positions. The wheels i are locked in position after each adjustment or change by means of the drop-pawls j , which fall by gravity into the notches of said wheels i . The pawls j are pivoted on a common shaft K 60 on the main actuating-bar A.

The printing-form c' is permanent and contains the names of the firm or other person or persons selling the goods to which the tickets are attached.

65 I now call attention to Figs. 9, 11, and 18, in which G designates a yoke attached at its upper end to the bar A. An operating-rod H

is screwed or otherwise connected to the said yoke and passes down through a tubular standard I, connecting with a foot-treadle J. 70 The platen k , which co-operates with the stapling devices in uniting the staple and ticket, is moved up to a position to thus co-operate and support the ribbon or ticket and the material or article to which said ticket is 75 to be attached just as the staple-driver a' is descending on the staple. The said platen k has a stem or extension k' , which projects down through a guide k'' and has attached to its lower end a weight k^3 . The lower end of 80 said extension k' is pivotally connected with a forked lever M, which is fulcrumed on a bearing N, attached to the bottom of the frame. (See Figs. 9 and 11.) The other end of the lever M is similarly connected to the 85 sides of an angular connection O, through which the operating-rod H passes. Surrounding said rod H and resting on the cross-piece of said connecting-piece O is a coil-spring O'. When the rod H is pressed down by the foot- 90 treadle, the bar A is immediately affected; but the lever M is not affected to elevate the platen k until the shoulder P of the yoke G engages with the top of the spring O'. This occurs just prior to the completion of the descent of the staple-plunger a . In the initial 95 movement of the platen k the knife-edges m and m' cut the ticket. The continued up movement of said platen holds the ticket against the plunger-guide g' in a position to 100 receive the staple and become united to the goods. The ink-pads normally rest against the type-wheels and form.

The mechanisms are timed to operate as follows: Pressure applied to the foot-treadle 105 J' will cause an immediate lowering of the bar A, and simultaneously therewith the shaft B is oscillated, the ink-pads begin to move away from their normal positions, the ribbon-feeding slide d and wire-feeding slide f'' begin to 110 move to positions from which to feed, the staple-depositor e moves away from the former e' , and the staple driver or plunger moves down. When the feed-slide d completes its movement to the position to engage the ribbon to 115 feed it and just before the completion of the movement of the wire-feeding slide f'' to the position to engage with the wire, the platen k begins to move up, the ticket is cut by the knife-edges, and the staple-plunger and the 120 platen k complete their movements toward each other simultaneously. Upon each down movement of the staple-plunger the ticket is stapled, and a staple is formed for the next 125 operation. The wire is cut just prior to each operation of forming a staple. The return or upward movements of the bar A and shaft B feed the ribbon and wire and move the staple-depositor over the former; also, the ink-pads are returned to the type-wheels and 130 form. I provide means for compelling a full downstroke of the rod H, so that an imperfect or incomplete feed of the paper and wire is at all times avoided. This means consists

of a ratchet H', attached to the standard, a sliding pawl H" engaging therewith and carried on a slide H³, guided on a bar H⁴. A connecting-bar H⁵ connects this slide with the 5 foot-treadle J'. When the slide H³ moves down, the pawl H" passes freely over the ratchet; but when the movement stops the said pawl immediately engages with the ratchet and prevents an upward movement 10 of the rod H until after the down movement is completed.

Having fully described my invention, I claim—

1. In a pin-ticket machine, the combination 15 with two primarily-movable members, means for vertically reciprocating one of said members and means for oscillating the other member operated by said vertically-reciprocable member, of ribbon-feeding mechanism actuated by said vertically-reciprocable member, printing mechanism carried on said vertically-reciprocable member, and inking-pads supported on said oscillating member.

2. In a pin-ticket machine, the combination 20 with two primarily-movable members, means for vertically reciprocating one of said members and means for oscillating the other of said members operated by said vertically-reciprocating member, of wire-feeding devices actuated by said oscillating member, and staple forming and driving mechanism actuated by said vertically-reciprocable member.

3. In a pin-ticket machine, the combination 25 with two primarily-movable members, means for vertically reciprocating one of said members and means for oscillating the other of said members operated by said vertically-reciprocating member, of wire-feeding mechanism actuated by said oscillating member, and ribbon-feeding, and staple forming and driving 30 mechanisms actuated simultaneously by said vertically-reciprocable member.

4. In a pin-ticket machine, the combination 35 with a primary vertically-reciprocating member, a primary oscillating member, and means for imparting such oscillating movement thereto operated by the said vertically-reciprocating member, of wire-feeding devices actuated by said oscillating member, a ribbon-feeding device actuated by said vertically-reciprocable member, a staple-former, a staple driver and depositor actuated by said vertically-reciprocable member.

5. In a pin-ticket machine, the combination 40 45 with a primary vertically-reciprocating member, a primary oscillating member, and means for imparting such oscillating movement to the latter from the former, of ribbon-feeding, and staple forming and driving devices actuated by said vertically-reciprocating member, wire-feeding devices actuated by said oscillating member, a platen disconnected from said members and adapted to coöperate with the staple-forming mechanism in uniting a 50 55 staple and ticket, and means for actuating said platen.

6. In a pin-ticket machine, the combination 60 with two primarily-movable members, means for vertically reciprocating one of said members, and means for oscillating the other of said members operated by said vertically-movable member, of ribbon-feeding mechanism, and staple forming and driving devices actuated by said vertically-reciprocating member, wire feeding and cutting devices actuated by said oscillating member, a platen 65 adapted to cut a ticket from said ribbon and to coöperate with the staple-driver in attaching said ticket, and independent means for actuating said platen. 70 75

7. In a pin-ticket machine, the combination 80 with two primarily-movable members, means for vertically reciprocating one of said members, and means operated by said vertically-reciprocating member for actuating said oscillating member, of a ribbon-feeding slide, means for operating said slide from the vertically-reciprocating member, type-wheels supported on and actuated by said vertically-reciprocating member, and inking-pads actuated by the oscillating member to ink said wheels. 85 90

8. In a pin-ticket machine, the combination 95 with two primarily-movable members, means for vertically reciprocating one of said members, and means operated by said vertically-reciprocating member for actuating the oscillating member, of a ribbon-feeding slide, means for actuating said slide from the vertically-reciprocating member, type-wheels 100 mounted on said vertically-reciprocating member, each of said type-wheels having an index-wheel by means of which said wheels may be regulated to vary the printing, and inking-pads actuated by the oscillating member to 105 ink said wheels.

9. In a pin-ticket machine, the combination 110 with an actuating-bar, of a ribbon-feeding device controlled thereby, and one or more series of type-wheels supported on said bar, telescopic tubes extending from said type-wheels, and an index-wheel on each of said telescopic tubes, the figures on said index-wheels corresponding with those on the type-wheels, and means for locking said index-wheels in position after each change in the location of the figures of the type-wheels. 115

10. In a pin-ticket machine, the combination 120 with a primary actuating member, and a paper-feeding device controlled thereby, of a series of type-wheels, telescopic shafts to which said wheels are attached, index-wheels on said shafts having indications corresponding with the figures on the type-wheels, and means engaging with each of said index-wheels to hold 125 them in position after an adjustment thereof.

11. In a pin-ticket machine, the combination 130 with a primary actuating member, of a ribbon-feeding device controlled thereby, a series of adjustable type-wheels to print upon said ribbon after each feed thereof, the said type-wheels having telescopic shafts, index-

wheels fixed to said shafts, the said index-wheels having indications thereon corresponding with the figures on the type-wheels and by means of which the positions of the 5 type-wheels are changed, drop-pawl engaging with said index-wheels to lock them, and inking-pads for said type-wheels.

In testimony that I claim the foregoing as my own I hereto affix my signature in presence of two witnesses.

WILLIAM G. METCALF.
